ROD BAKING OVEN OR THE LIKE

Carl F. Mayer, Lakewood, Ohio

Application May 15, 1939, Serial No. 273,719

5 Claims. (Cl. 263—10)

This invention relates generally to the class of industrial ovens, and more particularly to one in which the material or articles to be treated are loaded and unloaded in a vertical direction through the top of the oven.

A purpose to which the oven of my present invention is peculiarly suited is that of rod or wire baking, and for that reason it is so disclosed herein.

Rod baking ovens, or rod bakers, so-called, are used for drying rod or wire after it has been pickled and then dipped in a solution of lime or the like, as is well known to those acquainted with the art. The lime coating serves to neutralize the acid used in the pickling process. In the baking step, the rod or wire is heated or baked for the purpose of driving off the occluded hydrogen caused by the pickling operation and to leave deposited upon the wire or rod the dry lime that serves as a lubricant for the dies during the drawing operation.

The present embodiment of my invention is adapted to the prevailing arrangements of pickling and coating vats and naturally is intended for location at the concluding end of the so-called cleaning line.

While, as before stated, I have disclosed my invention in this particular association, it is to be understood that the invention has a broader application and that my improved oven or treating receptacle may be employed for various purposes, as in the drying of coatings upon articles, the treating of rubber articles, etc.

An object of my invention is the provision of an oven or receptacle of the character aforesaid, designed and arranged to be loaded and unloaded from the top, and that is provided with doors for effectively preventing any appreciable amount of heat loss or air spillage and obviating the objectionable escape of heat and fumes into the surrounding working quarters, thus promoting efficiency, economy, and comfort to the workmen; the doors opening and closing automatically as the load is lowered into the oven and as it is removed therefrom.

More specifically stated, the invention has for an object the provision of doors for the type of oven or receptacle referred to, that consists of counterweighted structures including shutters that close off the top of the oven, and which yield in a downward direction to the passage of the load as it is lowered into the oven or receptacle and automatically close thereover (the entire counterweighted structure of each door rocking during such lowering of the load), and the

shutters of which structures swing upwardly as the load is lifted from the oven and then returned to closed position by gravity.

Another object is to provide a circulating system by which the heating fluid is thoroughly diffused throughout the interior of the oven or baking chamber, and by which the oven or chamber is effectively ventilated. By reason of the manner in which the heating fluid is circulated and diffused, the work being treated is completely immersed in a bath of heated rapidly moving clean air, thus assuring thorough penetration of coils of rods or wire or the interstices of other articles being treated.

Other objects and advantages will appear as I proceed to describe the invention in detail by reference to the accompanying drawings wherein Fig. 1 is a plan view of my improved oven; Fig. 2 is a central vertical longitudinal section through the same, substantially on the line 2—2 of Fig. 3 (the heat exchangers, certain ducts associated therewith, etc., being shown in elevation); Fig. 3 is a section at right angles to Fig. 2, as indicated by the line 3—3 of the latter view; Fig. 4 is a sectional detail of the knee joint connection between the main elements of one of the doors and the hinge support of such door, with the door in closed position, and Figs. 5 and 6 are similar details showing the position of the parts when the door is swung open, first, as in Fig. 5, by the lowering of a load into the oven, and second, as in Fig. 6, by the lifting of a load from the oven.

The oven or baking chamber, designated generally by the reference character A, is enclosed by end walls 1 and 2, side walls 3 and 4 and a bottom wall 5. These walls are of the customary insulated kind employed in industrial ovens. The structure comprising these walls is supported by a framework, including post 8, from the bottom 9 of a pit so that said structure is located with its bottom wall 5 at about the floor level, the pit about the oven being covered by grating designated 10.

In the pit below the oven is an indirect heater designated generally by the reference character B, and the same is of the combustion type and may be fired with any suitable liquid or gaseous fuel. The heater includes a combustion chamber 15 and a tempering chamber 17 enclosed by walls of refractory material, the front and rear ones of which are designated 18 and 19, respectively. The front wall 18 is provided with one or more openings 20 for the accommodation of burners (not shown). Insulation is applied to the outer

sides of the walls of the combustion and tempering chambers, as indicated at 23.

Situated above and communicating with the tempering chamber is a space enclosed by insulated walls, the front and rear ones of which are designated 25 and 26, respectively, in Fig. 2; and occupying this space are heat exchangers 30. Fresh air and/or recirculated air is supplied from a fan or blower 32, through a duct 33 and a connection 34, to the inlet header 35 of the topmost or first heat exchanger. The outlet end of said exchanger is communicatively connected with the inlet end of the next lower or second heat exchanger through an elbow casing 36. The outlet of the second heat exchanger is similarly connected, through an elbow casing 37, with the inlet of the third heat exchanger, while the outlet thereof communicates, through the elbow casing 38, with the inlet of the fourth and final heat exchanger that exhausts, through its header 39, into the broad lower end of a duct 40 which separates toward its upper end into two branches 41 and 42 that lead upwardly through the bottom wall 5 of the oven. A drip pan 45 extends substantially horizontally across the oven a distance above the bottom wall 5, and the same drains through a waste pipe 46 (Fig. 3). The branch duct 41 extends along the underneath side of the drip pan midway between the side walls 3 and 4 to where it joins the lower end of an air distributing or diffusing unit 48. As will best appear from Fig. 3, the unit 48 is cross shaped in end elevation, the top of its upright portion rising to within a relatively short distance of the top of the oven, and the lateral arms of which are turned inwardly at right angles and follow the side walls 3 and 4, stopping short of the longitudinal center of the oven. The inwardly facing walls of this distributing unit are provided with a plurality of outlet openings 49 of such number and arrangement as to effect a very thorough diffusion of the heated fluid as it is discharged therefrom into the interior of the oven or chamber A. A similar fluid distributing unit 48a occupies the opposite end of the oven or chamber and communicates with the branch duct 42; and the outlet openings of the latter unit are designated 49a.

Extending transversely across the bottom wall 5 of the oven beneath the branch duct 41 is a return duct 50 whose left hand end (as the parts are viewed in Fig. 3) continues up along the side wall 3 and forms the vertical leg 51 of a fluid recovery unit designated generally by the reference numeral 53. Said unit includes, besides the vertical leg 51, a horizontal casing 55 that extends along the side wall 3 near the upper edge thereof throughout the length of the oven, and at its ends has right angle extensions 56 of smaller cross sectional area than the casing 55, the latter being provided with inlet openings 57, while the casing member 55 is provided with inlet openings 58. The leg 51 is also provided with inlet openings 60. Arranged adjacent the side wall 4 in opposed relation to the recovery unit 53 is one of identical nature, designated 53a, the parts whereof that correspond to the unit 53 being designated by the same reference characters, augmented by the exponent "a." The lower end of the upright 51a of the unit 53a is turned laterally through an opening in the side wall 4 immediately above the adjacent end of the duct 50 that also projects through an opening in said wall and both join a duct 65 that leads downwardly through an opening in the grating 10 into

the pit below and has communicative connection with the inlet of the previously mentioned fan or blower 32.

Disposed centrally and longitudinally of the oven or chamber A, and shown as resting on the drip pan 45, is a blow-off manifold 68 that is provided with upwardly diverging nozzles 69. This manifold has connection through a pipe 70 with a motor driven high pressure blower 71 whose intake communicates, through a pipe 73 (Fig. 2) with the lower end of the duct 65 adjacent the latter's connection with the inlet of the fan or blower 32. The purpose of this blow-off manifold is to direct blasts of hot air of high velocity against the articles being treated, as the coils of rod that hang upon the pin within the oven or chamber A, so as to quickly evaporate the moisture that drains to the bottom of said coils or other articles. This feature is disclosed and claimed in my co-jending application Serial No. 225,493, filed August 17, 1938, now Patent No. 2,235,559, issued March 18, 1941.

The products of combustion from the chambers 15 and 17 rise within the space occupied by the heat exchangers 30 wiping up along the tubes thereof as will more fully appear hereinafter, and said products are collected by a bonnet 75 which may exhaust to a stack or, as herein illustrated, communicate, through a conduit 76, with the inlet of an exhaust fan or blower 77 that may be driven by any suitable means.

As previously explained, the present embodiment of the invention is intended for use as a rod baker, and the rod, in the form of the coils C (Fig. 3), is suspended from a hook-like element or pin 80 that is secured to and depends from a beam 81, having attaching elements or eyes 82 for holding engagement with suitable handling apparatus, such as an overhead hoist and trolley by which the work is conveyed along the cleaning line, hereinbefore referred to. The load is adapted to be sustained within the oven or chamber A in drying or baking position by engagement of the ends of the beam 81 with the tops of the end walls 1 and 2.

In the interests of economy and greater efficiency, as well as comfort to the workmen by positively preventing appreciable escape or spillage of the hot gases and fumes into the surrounding working quarters, I equip the oven with doors designated generally by the reference numeral 85. Each door consists of an outer marginal plate 86 (Figs. 4 to 6) that is hingedly connected at 87 to a beam 88 that is supported by and between the end walls of the oven. The plate is reinforced or stiffened along its outer edge by an angle iron 89 which serves also as a counterbalancing weight that tends to retain the door in normal closed position, as illustrated in full lines in Fig. 3. The door is completed by a shutter 90 that has its outer edge overlapping the inner edge of the plate 86 and hinged thereto at 91. The free edge of the shutter may be reinforced by an angle 93. Thus it will be seen that I provide a sort of knee joint between the two main elements of the door, to wit, the shutter 90 and the plate 86, as best illustrated in Figs. 4 to 6, whereby the entire door structure may swing to the position indicated in dotted lines on the right side of Fig. 3 and in full lines in Fig. 5 when the load is being lowered into the oven or chamber A in opposition to the gravitational influence of the weight constituted of the angle iron 89. When the load is fully within the oven or chamber, it will have passed beyond reach

of the inner edges of the doors and they will automatically return to normal or closed position under the action of the aforesaid weight. It may here be explained that during the times the doors are open there will be a negligible escape of the gases and fumes due to the proximity of the inlet openings of the recovery units 53 and 53^a to the top of the oven.

When the load is lifted from the oven, it will engage the shutters 90 and swing them upwardly on their hinges far enough to permit the passage of the load, one of said shutters being so indicated in dotted lines on the left side of Fig. 3, the corresponding position of the right hand shutter being shown in full lines in Fig. 6 and to avoid any possibility of the shutters being thrown outwardly beyond a vertical position from which they could not close by gravity, I desire to include stops 95 that are carried by the plates 86. Suitable check means, such as dash pots, or bumpers or buffers may be used to retard or silence the closing of the doors.

Having thus described my invention, what I claim is:

1. In a top loading and unloading oven where-
with means is associated for lowering a load into
and lifting it from the oven, closure means for
the top of the oven that opens as the load passes
in both a downward and an upward direction,
said closure means comprising a shutter nor-
mally reposing in a substantially horizontal position
adjacent the top of the oven, a member sup-
ported for oscillation and with which the shutter
has pivotal connection so that the shutter may
swing relative to the member through an arc
above said horizontal position, the shutter and
member, by reason of the nature of the connec-
tion between them, moving in unison when the
shutter is swung through an arc below the afore-
said horizontal position, and means biasing the
member to the position it occupies when the
shutter is substantially horizontal.

2. In a top loading and unloading oven where-
with means is associated for lowering a load into
and lifting it from the oven, doors for clos-
ing the top of the oven that yield to the passing
of the load in both a downward and an upward

direction, each door comprising a shutter nor-
mally reposing in a substantially horizontal position
adjacent the top of the oven, a member sup-
ported for oscillation and with which the shutter
has pivotal connection so that the shutter may
swing relative to the member through an arc
above said horizontal position, the shutter and
member, by reason of the nature of the connec-
tion between them, moving in unison when the
shutter is swung through an arc below the afore-
said horizontal position, and means biasing the
member to the position it occupies when the
shutter is substantially horizontal.

3. In a top loading and unloading oven, a pair
of doors hinged to the oven structure adjacent
the top thereof that are adapted to be depressed
and opened as the load is lowered into the oven,
said doors being counterweighted so as to auto-
matically resume closed position when released,
and hinged shutters constituting portions of the
doors and arranged to be swung to open posi-
tion as the load is lifted and to return to closed
position by gravity when released.

4. In a top loading and unloading oven, a pair
of doors adjacent the top of the oven that are
adapted to be depressed and opened as the load
is lowered into the oven, each door consisting
of a marginal plate hinged to the oven structure
a substantial distance inwardly from the ad-
jacent side of said structure and extending out-
wardly over said side, a shutter hinged to the
plate near the inner edge of the latter, and means
tending to retain the plate and shutter in a
horizontal position.

5. In a top loading and unloading oven, a pair
of doors adjacent the top of the oven that are
adapted to be depressed and opened as the load
is lowered into the oven, each door consisting of
a marginal plate hinged to the oven structure
a substantial distance inwardly from the ad-
jacent side of said structure and extending out-
wardly over said side, a weight operatively con-
nected to the plate adjacent its outer edge, and
a shutter hinged to the top side of the plate near
the inner edge thereof so that the shutter has
a knee joint connection with the plate.

CARL F. MAYER.
